DESIGN FOR A BATHING SUIT OR SIMILAR ARTICLE

Bernard J. Hoffman, Jr., Forest Hills,
Long Island, N. Y.

Application December 2, 1939, Serial No. 88,632

Term of patent 14 years

To all whom it may concern:

Be it known that I, Bernard J. Hoffman, Jr., a citizen of the United States of America, residing in Forest Hills, Long Island, New York, county of Queens, State of New York, have invented a new, original, and ornamental Design for a Bathing Suit or Similar Article, of which the following is a specification, reference being had to the accompanying drawing, forming a part thereof.

Fig. 1 is a front perspective view of a bathing suit showing my new design; and

Fig. 2 is a rear view of the bathing suit shown in Fig. 1.

I claim:

The ornamental design for a bathing suit or similar article, substantially as shown.
